FILLING MACHINE FOR LIQUID CONTAINERS

Harry G. Mojonnier, Oak Park, Ill., assignor to
Mojonnier Bros. Co., Chicago, Ill., a corpora-
tion of Illinois

Application February 15, 1945, Serial No. 577,959

21 Claims. (Cl. 226—98)

1

This invention relates to the art of liquid handling, and concerns more particularly means and methods for effecting the filling of liquid containers or receptacles, such as bottles or the like, with liquids under pressure.

It is an object of the invention to provide a filling mechanism of the type defined, of improved construction, and improved operating characteristics.

More specifically stated, one of the objects of the invention is to provide a filling mechanism, specifically for liquids under pressure, which effects a more rapid flow and uniform distribution of the liquid into the container to be filled, which is so arranged as to facilitate cleaning and promote sanitation, and which is of simplified structure in relation to the operations performed, requiring fewer and more simplified power driven actuating mechanisms.

A further object of the invention is to provide a filling mechanism, specifically for liquids under pressure, wherein an effective separation between the liquid and the counter-pressure gas is maintained at all times and in an improved manner, facilitating and improving the filling operation, and promoting speed of operation and accuracy of measurement.

A still further object of the invention is to provide, in a filling mechanism for liquids, means and methods whereby the gas space within the container above the liquid, after filling, may be scavenged in an improved manner, and simultaneously charged with a desired gas or fluid, whereby to improve the quality of the finished product, and further promote accuracy of measurement.

Various other objects, advantages and features of the invention will be apparent from the following specification, when taken in connection with the accompanying drawings, wherein certain preferred embodiments are set forth for purposes of illustration.

In the drawings wherein like reference numerals refer to like parts throughout:

Fig. 1 is a general assembly view, primarily in vertical section, of a liquid filling apparatus constructed in accordance with and embodying the principles of the invention.

Fig. 2 is a top view of the mechanism of Fig. 1;

Fig. 3 is a vertical sectional view, on an enlarged scale and with parts broken away, of one of the filling units or heads, and taken as indicated by the line 3—3 of Fig. 2;

Figs. 4 and 5 are vertical sectional views of the filling valve, and associated parts, in different positions of operation;

Fig. 6 is a horizontal sectional view taken as indicated by the line 6—6 of Fig. 3, and more particularly showing the actuating valve spring support member, and associated parts;

Fig. 7 is a vertical sectional view of the sup-

port member, taken as indicated by the line 7—7 of Fig. 6;

Fig. 8 is a vertical sectional view of the inner valve seat member;

Fig. 9 is a vertical sectional view of the outer valve seat and support member, and taken as indicated by the irregular section line 9—9 of Fig. 10;

Fig. 10 is a horizontal sectional view, taken on the line 10—10 of Fig. 3, and showing the composite valve seat structure and associated parts;

Fig. 11 is a horizontal sectional view through the air release and upper valve structure, on the line 11—11 of Fig. 3;

Fig. 12 is a horizontal sectional view, on the line 12—12 of Fig. 3, and more particularly illustrating the shiftable filling valve member;

Fig. 13 is a vertical sectional view of the valve member taken as indicated by the line 13—13 of Fig. 12; and

Fig. 14 is a partial view illustrating a modified form of gas escape tube such as may be employed when the scavenging mechanism is inoperative.

In the drawings the invention has been shown incorporated into a filling mechanism of the type employed in the filling of bottles with carbonated liquids under pressure, as the invention in certain of its aspects is particularly adapted for use with a mechanism of this type. It is to be understood, however, that various principles and features of the invention may also be used in other types of liquid handling apparatus, including other types of liquid filling and measuring mechanisms.

Referring more particularly to the drawings, and first to the embodiment illustrated in Figs. 1—13, in Figs. 1 and 2 there is generally illustrated a bottle filling apparatus of the type utilized for filling bottles with carbonated beverage under pressure, and wherein the bottles are transmitted in a continuous automatic manner to the machine. The bottles are filled automatically as they are transmitted through the machine, and then ejected for transmission to a capping machine.

More specifically, the apparatus shown comprises a supply conveyor 10, along which the bottles 12 to be filled are transmitted in alignment by suitable means to the rotatable filling conveyor of the filling apparatus. The filling apparatus comprises a main frame or base 14 having a bearing block 16 upon which there is rotatably mounted an upright shaft or pedestal 18. Means is provided for effecting the rotation of the pedestal 18 in a step by step manner, the pedestal being rotated through a predetermined arc of travel upon each step of movement. As shown, such means comprises a worm wheel 20 fixed to

the lower end of the pedestal and adapted to be driven by a worm gear 22. The worm gear is driven by a suitable train of gears 24, 28, the latter of which is associated with and driven by a Geneva cam 30. This cam is actuated intermittently by a roller 32 carried on the end of a driving arm 34 adapted to be rotatably driven in any suitable manner, as for example by a belt driven pulley 36. As will be understood, as the arm 34 is rotatably driven, the Geneva drive comprising the roller 32 and the cam 30 imparts a step by step rotatable movement to the pedestal 18.

The filling conveyor comprises a bottle support plate 40 secured to the pedestal 18, for movement therewith, this support plate having a series of bottle cradles 42 arranged to transmit the bottles during the filling from the supply conveyor 10 to a discharge conveyor 44, Fig. 2, leading to the capping machine. A stationary ring-like cam 46, supported by a framework 47, cooperates with a plunger 48 associated with each cradle, so as to control the vertical positioning of the bottle as it is moved through the machine.

An annular filler bowl 50 is supported for movement with the pedestal 18 by a series of radial support arms or webs 52, the filler bowl being adapted to form a supply reservoir for the liquid to be introduced into the bottles. An annular cover plate 54 held in place by cap screws 56, Figs. 2 and 3, forms a cover for the filler bowl; whereas at predetermined spaced points, corresponding to the spacing of the cradles 42, the bottom of the bowl is provided with valve seat and support members 58, Figs. 2, 3 and 9, held in place by screws 60 and forming the support for a series of filling valve mechanisms later to be described. Each valve support plate carries a gasket 62, Fig. 3, against which the mouth of the bottle is brought into engagement by the cam mechanism 46-48 as the bottle leaves the supply conveyor 10, the engagement being maintained until the bottle is ready to be delivered to the discharge conveyor 44.

For the purpose of maintaining the filler bowl with an adequate liquid supply a supply pipe 64, Figs. 1 and 2, is provided communicating at one end with the filler bowl, and at its opposite end with a conduit or pipe 66 extending longitudinally of the pedestal 18 and rotatable therewith. By means of a packing structure 68 the movable pipe 66 connects with a stationary pipe section 70 in turn connecting with a supply pipe 72 leading to a suitable source of liquid supply under pressure, for example a carbonated beverage in the particular embodiment set forth. As will be understood, a reservoir of the liquid to be introduced into the bottles is thus constantly maintained under pressure and at a suitable level within the filler bowl, the liquid level being indicated at 74 in Fig. 3. Any suitable means may be employed for maintaining the liquid level constant, or within a predetermined range.

Means is also provided for supplying scavenging gas to the valve mechanisms, for a purpose subsequently to be described. As shown in Figs. 1 and 2, an annular pipe 76 embraces the filler bowl, the gas being supplied to the annular pipe by means of a supply pipe 78 having a rotatable section 80 extending longitudinally of the pedestal, and a stationary section 82, the movable and stationary pipe sections being connected by suitable packing means 84. The pipe 82 connects with a suitable source of gas under pressure, for example CO₂ in the particular embodiment set

forth. Preferably the gas pressure supply connecting with the pipe 82 is slightly higher than the pressure of the liquid source connected to the pipe 72.

The details of the foregoing mechanisms form no part of the present invention, except in so far as they cooperate with the filling devices and mechanisms hereinafter to be described.

As best shown in Figs. 9 and 10, each valve seat and support member 58 is provided with a pair of oppositely disposed upstanding projections 86 and 88 adapted by means of screws 90, Fig. 6, to be secured to and support a spring platform or support member 92. This spring support member is provided with a plurality of axial bores 94, three in the particular embodiment illustrated, adapted to slidably receive a series of vertically extending rods 96, Figs. 6 and 3. These rods at their lower ends are threaded into an annular valve member 98, Figs. 12 and 13, and at their upper ends are secured by means of set screws 100 to a housing member 102. An elongated, valve opening, compression spring 104 bears between the housing 102 and the spring platform support member 92.

Threaded into the central bore of the support platform 92 is an inner valve seat member 106, the detailed shaping of which is best shown in Fig. 8. This seat member has a lower annular portion 108 adapted, when the parts are in assembled position, to be in predetermined annular spaced relation with a portion 110 of the outer valve seat and support member 58, the parts 108 and 110 thus collectively forming an annular valve passage 109, Fig. 3, of predetermined size, and cooperable with an annular facing 112, Fig. 13, of the shiftable valve member 98. In the illustrated embodiment the annular valve passage 109 may, for example, be on the order of an inch in diameter and approximately one-sixteenth of an inch in width.

Referring further to Fig. 8, it will be seen that the inner valve seat member 106 is provided with an axially extending passage 114 terminating in a pair of coaxial threaded bores 116 and 118. A pair of tubes or pipes 120 and 122 are received, respectively, by the bores 116 and 118, and threadedly secured therein. These tubes, together with the passage 114, form a gas escape passage for gas from the bottle during the filling operation; whereas the annular passage between the parts 108 and 110, under control of the shiftable valve member 98-112, forms the restricted passageway of a filling conduit by which the liquid is introduced into the bottle, as will subsequently be described.

The upper end of the gas escape tube 120 carries a valve cap 124, resting by gravity thereon. The housing 102 carries a pin 126 adapted to engage the cap as the housing member is raised, so as to tilt the cap, as shown in Fig. 4. It will be seen that simultaneously as the main liquid valve 98 is opened, and the rods 96 and housing member 102 lifted, the valve cap 124 will be tilted into open position, permitting the escape of gas from the gas escape tube. Housing member 102 is provided with an orifice 128 so that gas exhausted from the gas escape tube may communicate freely with the gas space 130 within the filler bowl.

The upper portion of the housing member 102 carries a cap 132 adapted to be engaged, at a predetermined time during the movement of the bottle through the machine, and for a predetermined length of time, by an operating plunger or

rod 134, the upper end of which is adapted to be engaged and actuated by a stationary ring-like cam 136, Figs. 3 and 1, of suitable shape and contour, and suitably supported by framework 47. When the rod 134 is forced downwardly into engagement with the cap 132, the main liquid control valve 98 is forced into closed position against the action of spring 104, as shown in Fig. 5.

To seal the operating rod or plunger 134 against leakage it will be seen that there is provided a flexible bellows 138, Fig. 3, sealed at its upper end to a flange 140 formed on the plunger, and at its lower end to a plug member 142 held in compressed engagement against a gasket 144 by means of a screw cap 146 having threaded engagement with the filler bowl cover. A compression spring 148 normally urges the plunger upwardly into engagement with the cam 136.

Means is provided for introducing counter-pressure gas into the bottle, prior to the filling operation. As shown, this means comprises a pipe 150, Fig. 3, communicating at its upper end with the gas space 130 in the filler bowl. The lower end of pipe 150 communicates with a pair of passages 152 and 154 drilled through the filler bowl wall, the latter passage communicating with an annular channel 156 formed in the outer valve seat and support member 58. Channel 156 communicates with a drilled passage 158 in the valve block, the latter terminating in a pipe 160, the end of which extends upwardly into an annular channel 162, Fig. 8, formed in the inner valve seat member 106. It will be seen that by means of the conduits described, counter-pressure gas from the reservoir 130 may be introduced into the annular channel 162, and then downwardly into the bottle, positioned in sealing engagement against the gasket 62.

Flow of counter-pressure gas into the bottle is controlled by means of a ball valve 164, Fig. 3, normally spring urged into closed position by means of a compression spring 166, and adapted to be opened by means of an operating rod or plunger 168 under control of a fixed cam 170. As shown in Figs. 1 and 2, the cam 170 may be supported by certain of the framework uprights, such as indicated at 41' and 41'', disposed between the inlet and outlet conveyors. The operating plunger 168 may be sealed against fluid leakage and mounted in a manner similar to the plunger 134, as previously described.

Means is provided for exhausting or sniffling compressed gas from the bottle after the filling operation. As best shown in Fig. 3, this means comprises a valve member 172 normally urged into closed position by means of a compression spring 174, but adapted to be opened by plunger 176, under control of the fixed cam track 177. This cam track may be of generally arcuate form, as shown in Fig. 2, and suitably supported from framework 41. When the valve is opened, communication is established from the channel 156 to atmosphere, through the exhaust passage 178.

Means is also provided for controlling the introduction of the scavenging gas from the pipe 76 into the annular channel 162, previously described. As shown in Fig. 3, this means comprises a series of drilled passages 180, 182 and 184 forming communication between the annular channel 156 and the pipe 76, under control of a ball valve 186. This ball valve is normally spring urged into closed position, and adapted to be opened by means of a plunger 188 under control of the fixed cam track 177. Means for mounting 75

the plunger 188, and for sealing it, may be the same as previously set forth in reference to plungers 134 and 168.

In operation, after the bottle has been brought into sealed engagement with the gasket 62, and as the bottle reaches a predetermined filling station, plunger 168 is operated by cam 170 to momentarily open the valve 164. Counter-pressure gas from the space 130 is thereby introduced into the bottle. As the pressure within the bottle increases to substantially that of the filler bowl, the main liquid control valve 98, which is normally held closed by the filler bowl pressure, is opened by the spring 104 as shown in Fig. 4. Simultaneously with the opening of the valve 98, the pin 126 is lifted therewith, and the gas escape valve 124 is tilted into open position.

The gas inlet or counter-pressure valve 164 need be opened only momentarily, and accordingly is permitted to close as the valve 98 opens and the filling commences. During the liquid filling of the bottle, the displaced air therein escapes upwardly through tubes 122 and 120, and into the filler bowl gas space through the valve 124.

The tube 122 is open at the bottom, as indicated at 190, and is also provided with an opening or orifice 192 spaced upwardly from the bottom of the tube a predetermined distance. When the liquid level within the bottle reaches the opening 192, further escape of air from the bottle is prevented, and the filling operation thereupon automatically ceases. More particularly, the liquid passage 169, Fig. 3, is of such size that the surface tension of the liquid stops the passage of the liquid therethrough, and the filling operation ceases, immediately as the liquid level rises above the air escape opening 192. A predetermined quantity of air becomes trapped within the bottle and between the opening 192 and the valve passage 109.

In the continued movement of the bottle through the machine cam 136 becomes operative to depress plunger 134, as shown in Fig. 5, thereby forcing valve member 98 closed against the action of spring 104. Pin 126 moves downwardly, as a part of the valve structure, so that gas escape valve 124 simultaneously closes.

Further movement of the bottle turntable then causes cam 177 to become operative upon plunger 188 to open scavenge valve 186, whereby CO₂ gas at a pressure somewhat in excess of that within the bottle is admitted from the supply pipe 76 into the annular channel 162 within the inner valve seat member. This causes a pressure scavenging of the trapped air from the upper part

55 of the bottle, and the replacement thereof by pure CO₂ gas. It also causes the lowering of the liquid level accurately to the level of the pipe end 190. More particularly, as the scavenging gas is introduced, some of the trapped air within the bottle escapes by way of orifice 192, and upwardly through pipes 122 and 120, the positive pressure of the escaping air forcing the valve 124 upwardly from its seat. However, orifice 192 is sufficiently restricted in size so that the trapped air is also forced through the opening 190 and upwardly through the tube 122, and this escaping air carries with it all liquid and foam above the level of said opening 190.

60 Further movement of the bottle through the machine causes cam 177 to close scavenge valve 186, and thereafter operate plunger 176 to open the snift or vent valve 172. This latter operation permits the reduction of gas pressure within the bottle to atmospheric, after which the vent

valve is permitted to close. The filling operation is now complete, and the bottle may be lowered and transmitted to the discharge conveyor. As will be understood, after the venting operation plunger 134 may be permitted to restore to normal upper position, the filler bowl pressure becoming operative to hold the valve 98 closed.

As will be further understood, should the bottle break or become improperly seated against the gasket 62 during the filling operation, the escape of the counter-pressure from the bottle causes the filler-bowl pressure to automatically close the liquid valve 98, stopping the filling operation.

Attention is directed to the character of the annular valve passage 109. It will be seen that while the passage is of predetermined size, sufficient to stop the filling operation upon the cutting off of air escape through the tube 122, the valve passage is otherwise unrestricted and unimpeded. By this means a maximum and rapid filling rate is obtained. Also the liquid delivered therethrough is caused to impinge in an unbroken annular ring against the tapered surface 194 of the valve seat member 58 whereby to flow smoothly and with a minimum of foaming down the sides of the bottle. Still further, there is nothing in or associated with the valve passage 109 to become contaminated, and upon separation of members 106 and 58, the passage becomes completely exposed for inspection or cleaning, if necessary.

Attention is further directed to the fact that liquid is at all times maintained out of and away from the counter-pressure, scavenging, and vent gas passages in the structure. More particularly, pipes 120 and 122 which may become either wholly or partially filled with liquid in operation, are used only as gas escape tubes through which gas flows at only small pressure differential. The counter-pressure passages associated with the valve 164, the scavenging passages associated with valve 186, and the vent passages associated with the valve 172 are at all times maintained absolutely free of liquid, so that atomizing or the formation of vapor clouds either upon the introduction of the counter-pressure into the bottle, or upon scavenging, or venting, is precluded. Such vapor clouds, if formed, tend to cause a boiling and agitation of the liquid, increasing the overall filling time required, and also introducing inaccuracies in measurement. In connection with the maintaining of the counter-pressure, scavenging, and vent passages free of liquid, it will be seen that the discharge end of the tube 160 through which the counter-pressure, scavenging, and vent gases flow, exhausts into the annular channel 162 of the inner valve seat member 106 which is at all times maintained liquid free, and is above and away from the liquid flow passages.

The scavenging operations, enabled by the provision of the scavenging mechanism, insure the removal of foam from the top of the bottle, thus insuring accuracy of measurement. The scavenging also causes the charging of the gas space of the bottle with a desired gas, for example pure CO₂ in the illustrated embodiment, as distinguished from the air diluted gas within the gas

The structure comprises a minimum number of parts, in respect to the operations performed, facilitating sanitation and cleaning, and also requiring a minimum number of external operating mechanisms. In this connection it will be noted that the gas escape valve 124 and the liquid valve 98 are structurally interconnected

for correlative movement, so that only suitable liquid valve operating means, viz., the spring 104 for opening and plunger 134 for closing, need be provided.

In Fig. 14 a modified embodiment is illustrated, such as may be utilized for example with the scavenging mechanism disabled. The construction is the same except that scavenging is not employed, and a tube 122a is utilized, the same as tube 122 previously described, but without an opening corresponding to the orifice 192. In the use of the Fig. 14 tube 122a, the filling will progress only to the level of the bottom of the tube, to the opening 190a. At the end of the filling, the air space above the liquid in the bottle is thereupon vented, without the intermediate scavenging operation.

It is obvious that various changes may be made in the specific embodiments set forth without departing from the spirit of the invention. The invention is accordingly not to be limited to the specific embodiments shown and described, but only as indicated in the following claims.

The invention is hereby claimed as follows:

1. A filling mechanism for introducing liquids into containers comprising a liquid supply chamber, a gas escape tube adapted to project into a container and having an escape opening disposed at a predetermined level therein, a filling conduit for liquid interconnecting the supply chamber and the container, a substantially annular restricted passageway disposed to said conduit, said passageway being sufficiently small to stop liquid flow therethrough when the escape of gas through said escape opening is cut off, and said filling conduit being formed with a downwardly and inwardly tapered conical wall portion disposed vertically below said passageway and adapted to receive the liquid therefrom, the smaller diameter of said conical wall being less than the inner diameter of said annular passageway.

2. A filling mechanism for introducing liquids into containers comprising a supply chamber for liquid under pressure, a filling conduit for the liquid interconnecting the supply chamber and the container, a gas escape conduit arranged to conduct gases from the container during the filling operation, a counter-pressure conduit for admitting counter-pressure gas to the container prior to the filling operation, and means for maintaining said counter-pressure conduit free of liquid during the filling operation.

3. A filling mechanism for introducing liquids into containers comprising a liquid supply chamber, a filling conduit for the liquid interconnecting the supply chamber and the container, a gas escape conduit having an escape opening disposed at a predetermined level within the container arranged to conduct gases therefrom during the filling operation, said filling conduit having a restricted passageway disposed therein to stop liquid flow through the passageway when the escape of gas through the gas escape opening is cut off, a counter-pressure conduit for admitting counter-pressure gas to the container prior to the filling operation, and means for maintaining said counter-pressure conduit free of liquid during the filling operation.

4. A filling mechanism for introducing liquids into containers comprising a supply chamber for liquid under pressure, a filling conduit for the liquid interconnecting the supply chamber and the container, a gas escape conduit arranged to conduct gases from the container during the

filling operation, a counter-pressure conduit for admitting counter-pressure gas to the container prior to the filling operation, a vent conduit for venting pressure gas from the container after the filling operation, and means for maintaining said counter-pressure and vent conduits free of liquid during the filling operation.

5. A filling mechanism for introducing liquids into containers comprising a liquid supply chamber, a filling conduit for the liquid interconnecting the supply chamber and the container, a gas escape conduit having an escape opening disposed at a predetermined level within the container arranged to conduct gases therefrom during the filling operation, said filling conduit having a restricted passageway disposed therein to stop liquid flow through the passageway when the escape of gas through the gas escape opening is cut off, a counter-pressure conduit for admitting counter-pressure gas to the container prior to the filling operation, a vent conduit for venting pressure gas from the container after the filling operation, and means for maintaining said vent conduit and said counter-pressure conduit free of liquid during the filling operation.

6. A filling mechanism for introducing liquids into containers comprising a liquid supply chamber, a filling conduit for the liquid interconnecting the supply chamber and the container, a gas escape conduit having an escape opening disposed at a predetermined level in the container, said filling conduit having a control valve and a restricted passageway disposed in the conduit for stopping liquid flow therethrough when the escape of gas through said escape opening is cut off, a counter-pressure conduit for admitting counter-pressure gas to the container prior to the filling operation, and means comprising a conduit portion extending to a point above and away from the filling conduit for maintaining said counter-pressure conduit free of liquid during the filling operation.

7. The method of introducing liquids into containers which comprises introducing counter-pressure gas into the container to establish a predetermined pressure condition therein, filling the container to establish a predetermined liquid level, and scavenging the first named gas from the gas space within the container above the liquid level, while simultaneously introducing a gas of predetermined quality therein.

8. A filling mechanism for introducing liquids into containers comprising a liquid supply chamber, a gas escape tube adapted to project into a container and having an escape opening disposed at a predetermined level therein, a filling conduit for liquid interconnecting the supply chamber and the container, a restricted passageway disposed in said conduit, said passageway being sufficiently small to stop liquid flow therethrough when the escape of gas through said escape opening is cut off, and means for scavenging gas from the container above the liquid level while simultaneously introducing a gas of predetermined quality therein.

9. A filling mechanism for introducing liquids into containers comprising a supply chamber for liquid under pressure, a filling conduit for the liquid interconnecting the supply chamber and the container, a gas escape tube adapted to project into the container and having an escape opening disposed at a predetermined level therein, said filling conduit having a restricted passageway for stopping liquid flow therethrough when the escape of gas through said escape open-

ing is cut off, a counter-pressure conduit for admitting counter-pressure gas to the container prior to the filling operation, and a scavenging conduit for admitting scavenging gas to the container subsequent to the filling operation to scavenge the counter-pressure gas from the gas space in the container above the liquid level.

10. A filling mechanism for introducing liquids into containers comprising a supply chamber for liquid, a filling conduit for the liquid interconnecting the supply chamber and the container, a filling valve for controlling liquid flow through the filling conduit, a gas escape conduit arranged to conduct gases from the container during the filling operation, an escape valve for controlling gas flow through the escape conduit, means for operating the filling valve, said filling valve actuating the escape valve therewith, and a restricted orifice in the filling conduit to cut off flow therethrough upon the cutting off of gas flow through the gas escape conduit.

11. A filling mechanism for introducing liquids into containers comprising a supply chamber for liquid under pressure, a filling conduit for the liquid interconnecting the supply chamber and the container, a filling valve for controlling liquid flow through the filling conduit, a gas escape conduit arranged to conduct gases from the container during the filling operation, an escape valve for controlling gas flow through the escape conduit, and means for operating the filling valve, said filling valve actuating the escape valve therewith, a counter-pressure conduit for admitting counter-pressure gas to the container prior to the filling operation, a counter-pressure valve for controlling gas flow through the counter-pressure conduit, and means for operating said counter-pressure valve.

12. A filling mechanism for introducing liquids into containers comprising a supply chamber for liquid under pressure, a filling conduit for the liquid interconnecting the supply chamber and the container, a shiftable filling valve for controlling liquid flow through the filling conduit, a gas escape tube for conducting gases from the container during the filling operation, a shiftable escape valve for controlling gas flow through said escape tube, a spring for operating the filling valve in one direction, power mechanism for shifting the filling valve in the opposite direction, said filling valve shifting the escape valve simultaneously therewith, and a restricted orifice in the filling conduit for cutting off flow therethrough upon the cutting off of gas flow through the gas escape tube.

13. A filling mechanism for introducing liquids into containers comprising a supply chamber for liquid under pressure, a filling conduit for the liquid interconnecting the supply chamber and the container, a shiftable filling valve for controlling liquid flow through the filling conduit, a gas escape tube for conducting gases from the container during the filling operation, a shiftable escape valve for controlling gas flow through said escape tube, means for introducing counter-pressure gas into the container including a counter-pressure control valve and means for controlling the functioning thereof, a spring for operating the filling valve in one direction when counter-pressure within the container reaches a predetermined value, and power mechanism for shifting the filling valve in the opposite direction, said filling valve shifting the escape valve simultaneously therewith.

14. A filling mechanism for introducing liquids

into containers comprising a support for a container, a supply chamber for liquid under pressure, a filling conduit for the liquid interconnecting the supply chamber and the container, a shiftable filling valve for controlling liquid flow through the filling conduit, a gas escape tube fixed in respect to the container support during the filling operation and adapted to project into the container and having an escape opening disposed at a predetermined level therein, said filling conduit having a restricted passageway formed therein for stopping liquid flow therethrough when the escape of gas through the escape opening is cut off, a shiftable escape valve for controlling the flow through said escape tube, means for admitting counter-pressure into the container prior to the filling operation, and means for venting pressure gas from the container after the filling operation.

15. A filling mechanism for introducing liquids into containers comprising a liquid supply chamber, a gas escape tube adapted to project into a container and having an escape opening disposed at a predetermined level therein, a filling conduit for liquid interconnecting the supply chamber and the container, and means defining a restricted passageway disposed in said conduit, said passageway being formed by a pair of juxtaposed conduit portions defining the lateral limits of the liquid body immediately thereunder, the space between said portions being open and unobstructed but sufficiently small to stop liquid flow therethrough when the escape of gas through said escape opening is cut off.

16. A filling mechanism for introducing liquids into containers comprising a liquid supply chamber, a gas escape tube adapted to project into a container and having an escape opening disposed at a predetermined level therein, a filling conduit for liquid interconnecting the supply chamber and the container, and means defining a restricted passageway disposed in said conduit above the level of the escape opening of the gas escape tube, said passageway comprising a single opening transmitting the entire liquid flow through said filling conduit, and said opening being open and unobstructed but sufficiently small to cause the surface tension of the liquid to stop liquid flow therethrough when the escape of gas through the escape opening is cut off.

17. A filling mechanism for introducing liquids into containers comprising a liquid supply chamber, a gas escape tube adapted to project into a container and having an escape opening disposed at a predetermined level therein, a filling conduit for liquid interconnecting the supply chamber and the container, and means defining a restricted passageway disposed in said conduit above the level of the escape opening of the gas escape tube, said passageway being formed by juxtaposed conduit portions defining an annular opening, the space between said portions being open and unobstructed but sufficiently small to cause the surface tension of the liquid to stop liquid flow therethrough when the escape of gas through the escape opening is cut off.

18. A filling mechanism for introducing liquids into containers comprising a liquid supply chamber, a gas escape tube adapted to project into a container and having an escape opening disposed at a predetermined level therein, a filling conduit for liquid interconnecting the supply chamber and the container, and means defining a restricted passageway disposed in said conduit, said passageway transmitting the entire liquid

flow through the filling conduit, and said passageway being formed by a pair of relatively separable members separable to facilitate the cleaning of the flow space therebetween, the space between said members being open and unobstructed but sufficiently small to stop liquid flow therethrough when the escape of gas through the escape opening is cut off.

19. A filling mechanism for introducing liquids into containers comprising a liquid supply chamber, a gas escape tube adapted to project into a container and having an escape opening disposed at a predetermined level therein, a filling conduit for liquid interconnecting the supply chamber and the container, and means defining a restricted passageway disposed in said conduit, said passageway being formed by a pair of juxtaposed members defining an annular opening therebetween, said members being separable to facilitate the cleaning of said opening, and said opening being unobstructed but sufficiently small to stop liquid flow therethrough when the escape of gas through the escape opening is cut off.

20. A filling mechanism for introducing liquids into containers comprising a liquid supply chamber, a gas escape tube adapted to project into a container and having an escape opening disposed at a predetermined level therein, a filling conduit for liquid interconnecting the supply chamber and the container, and means defining a restricted passageway disposed in said conduit, said passageway being formed by a pair of spaced juxtaposed conduit portions having a dimension longitudinally of the passageway greater than the flow space therebetween, said flow space being open and unobstructed but sufficiently small to stop liquid flow therethrough when the escape of gas through the escape opening is cut off.

21. A filling mechanism for introducing liquids into containers comprising a reservoir adapted to contain a supply of liquid under pressure, a gas escape tube adapted to project into a container and having an escape opening disposed at a predetermined level therein, a filling conduit for liquid interconnecting said reservoir and the container, said gas escape tube having a portion disposed within the filling conduit, gasket means for sealing the container to the filling conduit in a fluid-tight connection, and a restricted passageway disposed in the filling conduit above the level of the escape opening of the gas escape tube, said passageway comprising an elongated narrow opening having its minimum flow area dimension sufficiently small to cause the surface tension of the liquid to stop gravity liquid flow through all parts of the passageway when the escape of gas through said escape opening is cut off.

HARRY G. MOJONNIER.
